ABSTRACT

A memory device including a buffer register for storing input data and a main shift register having addresses arranged in series so as to store input data supplied from said buffer register in a specified address, wherein, in case input data being stored in the main register has more digits than those initially designed for the prescribed address of the main shift register, there is serially connected to the main shift register a supplementary shift register capable of handling numerous digits so as to store said excess digits as a temporary extension of the capacity of the main shift register. There is formed a path of circulatory shifting between the input section of the main shift register and the position of the least significant digit which is detected by detecting means to have flowed over to said supplementary shift register when the specified address of the main shift register is fully filled with inputs from the buffer register and there is connected between the main shift register and supplementary shift register means for disconnecting the supplementary shift register from the main shift register at the beginning of cycle of circulatory shifting in said main shift register.

**MEMORY DEVICE HAVING MAIN SHIFT
REGISTER AND SUPPLEMENTARY SHIFT
REGISTER**

This invention relates to a memory device capable of effectively utilizing the capacity of a shift register by its temporary extension.

Memory devices known to date include a dynamic type for storing data while keeping it successively shifted and a static type capable of suitably shifting data upon receipt of instructions, though said data may be kept at rest up to that point. With these prior art memory devices, the numbers of characters or digits of data being stored are projected in advance and storing is effected by allotting particular characters or digits to the specified addresses. To effect a storing operation smoothly, therefore, the conventional memory device should be designed with full allowance for the numbers of characters or digits being recorded. In fact, however, the prior memory device has failed to utilize most effectively the prescribed address of a shift register which is to be stored with the originally designed number of characters. Namely, part of the address sometimes is left unused.

It is accordingly the object of this invention to provide a memory device free from the above-mentioned drawbacks which is provided with a shift register unit capable of handling varying numbers of characters or digits by controlling the storing capacity of the specified address according to the number of characters or digits included in data being stored, thereby effectively utilizing the storing capacity of the shift register unit without occurrence of unused portions in the specified address.

SUMMARY OF THE INVENTION

To attain the aforesaid object, the memory device of this invention has a supplementary shift register capable of handling numerous characters or digits which is serially connected to a main shift register having addresses arranged in series. Where an input data from a buffer register has more digits than those initially designed for the prescribed address of the main shift register, the supplementary shift register temporarily stores said overflowing digits. When the prescribed address of the main shift register is fully stored with data from the buffer register, said overflowing digits conducted to the supplementary shift register are detected by detecting means and the resultant detection signal is fed back to the input terminal of the main shift register through a path of circulatory shifting. The supplementary shift register is disconnected from the main shift register at the beginning of each cycle of circulatory shifting in the main shift register, thereby providing a shift register unit capable of handling varying numbers of characters or digits with its storing capacity suitably controlled.

Accordingly, the shift register unit of this invention does not require the storing capacity of a prescribed address to be defined in advance according to the number of the characters or digits of data being stored, as is the case with the prior art memory device. Namely, this invention enables the storing capacity of the addresses included in the shift register unit to be freely increased as needed, thus prominently elevating its stor-

ing efficiency by effective utilization of its initially set storing capacity.

The appended drawing is a circuit diagram of the memory device of this invention.

There will now be described this invention by reference to the appended drawing. Notation SR₁ denotes a main shift register which is a dynamic type designed to store digits in series and in consequence having digit addresses arranged in series (said arrangement comprises, for example, 4 bits). To said main shift register SR₁ is serially connected a supplementary shift register SR₂ which is formed of a dynamic shift register actuated in synchronization with the main shift register SR₁. Said supplementary shift register SR₂ has a capacity of 15 storing digits D₁ to D_n (a maximum word length of, for example, 12 digits), and is so designed as to successively store data shifted from the position of the digit D₀ of the final output section of the main shift register SR₁. To the position of the digit D₀ of the final output section of the main register SR₁ is connected a mark signal detecting circuit MD for detecting a start code F and a space code S and generating an output signal of "1" from the F or S output terminal thereof according to the type of code detected. There is provided a 20 ring counter with count numbers 0, 1, 2, ..., n so set as to correspond to the digit D₀ of the final output section of the main shift register SR₁ and the digits D₁ to D_n of the supplementary shift register SR₂ respectively. One of AND circuits B₀ to B_n is opened according to 25 the number of counts made by the ring counter RC to feed back a signal associated with the corresponding digit of the supplementary shift register SR₂ through an OR circuit 01, 03 and AND circuit A₁ to the input section of the main shift register SR₁, thus forming a path 30 of circulatory shifting. This path of circulatory shifting can also be provided by an n-value counter fitted with a decoder. In the case of said n-value counter, the input section of the main shift register SR₁ is provided with an adder ADD, which is supplied with data from a 35 buffer register BR. This buffer register BR is designed to temporarily store circulating data and input data, and comprises, for example, a static type, which, upon receipt of instructions, causes data stored therein to be shifted, producing an output signal. An output signal from said buffer register BR and a carry signal from said adder ADD are supplied through an OR circuit O₂ to an input value detecting circuit BRD. This detecting circuit BRD produces an output signal of "1" while the 40 buffer register contains data being delivered to the main shift register SR₁, thereby judging whether the final digit still remains stored in the buffer register BR. Said detecting circuit BRD may be a type designed to count the number of digits included in a given number. Further, an address for storing data is specified by an 45 address signal which, in turn, is counted by an address counter ADC. Said address counter ADC counts the number of an address being specified and later counts down in succession, each time the prescribed address 50 of the main shift register SR₁ advances by being shifted. Upon completion of counting required to specify an address, said address counter ADC produces an output signal of "1".

With the aforementioned type of memory device, there are recorded in the main shift register SR₁, the marks indicated in Table 1 below by a mark signal generating circuit M.

TABLE I.—MARKS RECORDED IN THE MAIN SHIFT REGISTER

t	Operation	BR	SR ₁	D ₀	D ₁	D ₂	D ₃	D ₄	RC	ADC	F/F ₁	F/F ₂	Y=1
	Writing of marks		SS.....SSS	F						0	0	0	0

The mark signal generating circuit M records first a start code F and then a space code S delivered from the initial section of each cycle of circulatory shifting in the main shift register SR₁. In this case, the gate terminal of an AND circuit A₁ provided in a path for transmitting signals from the mark signal generating circuit M is kept in a state of "1" by an output from the mark signal generating circuit M. Under this condition, there are received neither writing instructions nor input data. The input value detecting circuit BRD associated with the buffer register BR produces an output of "0," and the reset terminal of a flip-flop circuit FF₂ is supplied with a signal of "1" through a NOT circuit I₁. A "0" output from said flip-flop circuit FF₂ is converted to a signal of "1" through a NOT circuit I₂ to be supplied to the AND circuit A₁. At this time, signals representing the start code F and space code S which are supplied from the mark signal generating circuit M pass through an OR circuit O₃, the opened AND circuit A₁, and adder ADD and are stored in the main shift register SR₁, which is actuated at this time by clock pulses from a clock pulse generator CR. When the start code F is brought to the position of the digit D₀ of the final output section of the main shift register SR₁, the mark signal detecting circuit MD detects said start code F, the resultant detection signal resetting the ring counter RC. Accordingly, an AND circuit BO is opened to cause the recorded start code F to be subjected to circulatory shifting through the OR circuit O₃, AND circuit A₁ and adder ADD.

Where, under this condition, there are given instructions to record data 365 in the address 1, then said data 365 is first recorded in the buffer register BR. At this time, the address counter ADC counts 1 as an address signal. Accordingly, the input value detecting circuit BRD detects the value of said data delivered from the buffer register BR, and generates a signal of Y=1, which in turn is conducted to an AND circuit A₂. Where, under this condition, there is received a signal denoting writing instructions M₁, said signal is supplied to an AND circuit A₃ through an OR circuit O₄. At this time, the start code F recorded in the main shift register SR₁ is already subjected to circulatory shifting. When, therefore, said start code F reaches the position of the digit D₀ of the final output section of the main shift reg-

ister SR₁, the mark signal detecting circuit MD detects said start code F. The resultant detection output opens the gate of the AND circuit A₂ and resets a flip-flop circuit FF₃, causing a signal of writing instructions MI to be supplied to an AND circuit A₄. Said AND circuit A₄ is supplied with a gate signal through an OR circuit O₆ upon receipt of output signals derived from detection of the marks F and S by the mark signal detecting circuit MD. The aforesaid signal of writing instructions MI so acts as to cause the address counter ADC to count down. Namely, each time there takes place one shift in the main shift register SR₁, the address counter ADC counts down by one. In this case, the address counter counts 1 to specify the address 1. When, therefore, the start code F is brought to the position of the digit D₀ of the final output section of the main shift register SR₁, and then shifted back to the input section thereof, then the address counter ADC counts 0. Accordingly, the output signal of "1" from said address counter ADC resets the flip-flop circuit FF₃, resulting in the state indicated under the item of t=2 in the aforesaid Table 1.

Where the address counter counts down to 0, it produces an output signal of "1." This signal of "1" is supplied to the flip-flop circuit FF₁ to set it and also to the AND circuit A₂ as a gate signal. As the result, the flip-flop circuit FF₁ produces an output signal of "1," and the AND circuit A₂ is supplied with the aforesaid signal of Y=1 and a signal derived from detection of the space code S by the mark signal detecting circuit MD. At this time, the flip-flop circuit FF₂ is also set to produce an output signal of "1." An output signal of "1" from the flip-flop circuit FF₁ opens an AND circuit A₅, which in turn produces an output signal of "1" to open an AND circuit A₆. Accordingly, the least significant digit 5 stored in the buffer register BR is brought to the input section of the main shift register SR₁ through the adder ADD, presenting the state shown under the item of t=3 in Table 1. At this time, the main register SR₁ has no more space to store said digit 5. However, this digit 5 overflows to the position of the digit D₁ of the supplementary shift register SR₂ to be stored therein. Clock pulses from the clock pulse generator CR are supplied to an AND circuit A₇ together with an output signal from the flip-flop circuit FF₁, causing the buffer register BR to effect shifting upon receipt of instructions. At

this time, the ring counter RC counts 1 upon receipt of an output signal from the flip-flop circuit FF₂ to open the AND circuit B₁, and the AND circuit A₁ remains closed, preventing the occurrence of circulatory shifting.

Later when the clock pulse generator CR delivers clock pulses, data recorded in the buffer register BR is conducted to the main shift register SR₁ as shown under the items of t=4 and t=5 in Table 1, and the space code S forced out of the main register SR₁ is recorded in the supplementary shift register SR₂ up to the position of the digit D₃, causing the ring counter RC to count 3. When data stored in the buffer register BR is fully brought into the main shift register SR₁, the input value detecting circuit BRD produces an output of Y=0 to close the gate of the AND circuit A₂, thereby resetting the flip-flop circuit FF₂ through the NOT circuit I₁ as well as the flip-flop circuit FF₁ through an AND circuit A₁₁ and an OR circuit O₇. As a result, the AND circuit A₁ is opened to cause the position of the digit D₃ of the supplementary shift register SR₂ to be connected to the input section of the main shift register SR₁ through the AND circuit B₃ which is opened when the ring counter RC counts 3, as well as through the adder ADD, thus giving rise to circulatory shifting and completing the writing of data. Where the start code F is brought to the position of the digit D₀ of the final output section of the main shift register SR₁ due to said circulatory shifting, the mark signal detecting circuit MD generates an output as the result of detecting said start code F to reset the ring counter RC, thereby shutting off the space code S from the positions of the digits D₁ to D₃ of the supplementary shift register SR₂. Accordingly, there is formed a path of circulatory shifting between the position of the digit D₀ of the output section and the input section of the main shift register SR₁, retaining the data recorded at that time. Thus is completed the writing of data 365 in the address 1.

Where data 1971 is to be further recorded in the address 3, said writing is effected by storing said data 1971 first in the buffer register BR as in the preceding case and causing the address counter to count 3. In the case of the count 1, counting is brought to an end upon detection of the start code F by the mark signal detecting circuit MD. In the case of the count 3, however, the address counter ADC further continues operation by counting down in succession until it counts 0, because there is introduced a signal derived from the detection of the space code S even after the detection of the start code F.

There is now described the case of reading out stored data. Where there is to be read out the data stored, for example, in the address 1, then the address counter ADC is first made to count 1. A signal of readout instructions MO generated at this time is conducted as a gate signal to an AND circuit A₉ connected to the input section of the buffer register BR, as well as to an AND circuit A₁₀. Where, under this condition, the space code S remains at the position of the digit D₀ of the final output section of the main shift register SR₁, the AND circuit A₁₀ is opened by an output from the mark signal detecting circuit MD to reset the flip-flop circuit FF₁ through the OR circuit O₇. Where, however, the start code F arrives at the position of the digit D₀ of the final output section of the main shift register SR₁, the AND circuit A₁₀ is closed, and the AND circuit A₉ is opened which is supplied with said readout signal MO,

causing the address counter ADC to count down through the AND circuit A₄. When it counts 0 through the above-mentioned operation, the address counter ADC produces an output of "1," which is supplied to the flip-flop circuit FF₁ to set it. Where the start code F is introduced into the input section of the main shift register SR₁ and the least significant digit of the stored data 365 is brought to the position of the digit D₀ of the final output section of the main shift register SR₁, then an output signal of "1" of the flip-flop circuit FF₁ is conducted to the AND circuit A₉, and the least significant digit 5 conducted to said D₀ position is brought back to the buffer register BR through the AND circuit B₀, OR circuit O₃, AND circuit A₁ and AND circuit A₉. Thus with the progress of shifting effected by clock pulses, the data 365 is introduced into the buffer register BR through the readout operation. In this case, data obtained from the D₀ position passes through the adder ADD to be shifted also through the main shift register SR₁, thereby retaining the data stored at that time. Upon completion of the aforesaid readout operation, the mark signal detecting circuit MD again detects the space code S brought to the position of the digit D₀ of the final output section of the main shift register SR₁ to reset the flip-flop circuit FF₁, restoring the original stored data making circulatory shifting.

There will now be described the case where there is added fresh data 721 to the stored data 365. As in the case of writing, said fresh data 721 is first recorded in the buffer register BR and the address counter ADC is set at 1. Where, under this condition, there is introduced a signal of writing instructions MI, and the start code F is brought to the position of the digit D₀ of the final output section of the main shift register SR₁, then the AND circuit A₃, and the AND circuit A₄ produce an output to cause the address counter ADC to count down to set the flip-flop circuit FF₁. Where, under this condition, the start code F arrives at the input section of the main shift register SR₁, the AND circuit A₄ again generates an output to open the AND circuits A₅ and A₆, thereby delivering the data stored in the buffer register BR to the adder ADD. Though, in this case, the input value detecting circuit BRD produces an output of Y=1, the flip-flop circuit FF₂ is not set and the AND circuit A₁ remains open, because there are already brought the start code F and the data 365 to the output section of the main register SR₁. Upon impression of clock pulses, therefore, the data 365 stored in the main shift register SR₁ is added to the adder ADD, starting with the least significant digit 5, so as to be added to the data 721 already brought to the adder ADD from the buffer register BR. In this case, addition of 365 and 721 results in a 4-bit number of 1086. When the third digits 3 and 7 are added together, the adder ADD produces a carry signal, which in turn is supplied to the input value detecting circuit BRD. Thus even when the buffer register BR is fully emptied of data stored therein, said carry signal causes the input value detecting circuit BRD to retain a state of Y=1 up to the fourth digit. When the third digit stored in the main shift register SR₁ is supplied to the adder ADD, the space code S is brought to the position of the digit D₀ of the final output section of the main shift register SR₁, and the mark signal detecting circuit MD generates an output as the result of detecting said space code S. Accordingly, the flip-flop circuit FF₂ is set to bring circulatory shifting to an end with the AND circuit A₁ shut off.

When the fourth digit of the four-digit sum 1086 is going to be stored in the main shift register SR₁, the least significant digit 6 thereof overflows to the supplementary shift register SR₂. The ring counter RC is operated in the same manner as in writing to open the AND circuit B₁. Where the carry signal is extinguished, the input value detecting circuit BRD generates an output of Y=0 to reset the flip-flop circuits FF₁ and FF₂, giving rise to circulatory shifting. Where, therefore, the start code F is brought to the position of the digit D₀ of the final output section of the main shift register SR₁, the ring counter RC is reset.

The foregoing embodiment refers to the case where a memory device was operated with serial 4-bit signals. However, this invention is not limited to this number of bits, but may also enable a memory device to be operated with serial 5-bit signals or parallel n-bit signals.

I claim:

1. A memory device comprising:
a buffer register for storing input data;
a main shift register for storing in specified addresses input data from said buffer register in the form of serially arranged words by use of word dividing codes inserted into each address;
a supplementary shift register serially connected to said main shift register for temporarily storing excess digits when the input data from said buffer register has more digits than those already registered in the addresses of said main shift register, the already registered digits corresponding to the storage capacity of said main shift register;

5 by-pass means for feeding back data of said excess digits registered in said supplementary shift register to an input terminal of said main shift register when input data from said buffer register has been fully filled in the addresses of said main shift register; and

10 disconnecting means coupled to said by-pass means for disconnecting said supplementary shift register from said main shift register by rendering said by-pass means inoperative in a particular timing corresponding to each cycle of circulatory shifting in said main shift register.

15 2. A memory device according to claim 1 wherein said by-pass means comprises a ring counter for counting digits and AND circuits coupled thereto, said AND circuits being responsive to the outputs from said ring counter and outputs corresponding to said excess digits from said supplementary shift register to form gate input signals.

20 3. A memory device according to claim 1 wherein said disconnecting means comprises a mark signal detecting means comprises a mark signal detecting means coupled to said main shift register and adapted to render said by-pass means inoperative responsive to detection of a given mark signal.

25 4. A memory device according to claim 1 wherein said by-pass means includes means responsive to detection of at least a start code in the stored data to render 30 said bypass means inoperative.
